A. H. STEVENS.
ANILIN REDUCER.
APPLICATION FILED MAR. 25, 1918.

1,267,819.

Patented May 28, 1918.

UNITED STATES PATENT OFFICE.

ALFRED H. STEVENS, OF BROOKLYN, NEW YORK, ASSIGNOR TO STEVENS BROTHERS, OF NEW YORK, N. Y., A PARTNERSHIP.

ANILIN-REDUCER.

1,267,819.

Specification of Letters Patent. Patented May 28, 1918.

Application filed March 25, 1918. Serial No. 224,452.

To all whom it may concern:

Be it known that I, ALFRED H. STEVENS, a citizen of the United States, residing in the city of New York, borough of Brooklyn, in the county of Kings and State of New York, have invented a certain new and useful Improvement in Anilin-Reducers, of which the following is a specification.

The invention relates to stirring or mixing machines such as are employed in the manufacture of anilin and analogous products.

In the process of reducing anilin, nitrobenzol is treated with iron filings, hydrochloric acid, and steam, in a suitable tank equipped with horizontally disposed arms by which the mass is mixed. The arms, each usually a single casting, are subjected not only to the corrosive action of the acid but also to the erosive or abrasive action of the mass, with the result that the arms are short-lived and must be replaced at short intervals, entailing a corresponding loss economically both in time and material.

The object of the invention is to obviate the above objectionable features by providing stirring arms so constructed as to endure the wear for long periods, which may be readily conditioned for further service when partially worn, and the replacement easily and quickly effected.

The invention consists in certain novel features and details of construction and arrangement by which the above objects are attained, to be hereinafter described and claimed.

The accompanying drawings form a part of this specification and show the invention as it has been carried out in practice.

Figure 1 is a side elevation of an anilin reducing tank equipped with the improved arms, and partly in vertical section.

The remaining figures are on a larger scale.

Fig. 2 is a vertical section through the lower portion of the tank, the step for the shaft, and the arms thereon, with portions of the latter in elevation.

Fig. 3 is a horizontal section through the tank and shaft, showing the arms in plan view.

Fig. 4 is a side view of one of the rabble blades of which the arms are composed.

Fig. 5 is a view of the under face of one of the blades.

Fig. 6 is a vertical longitudinal section of a blade.

Fig. 7 is an elevation showing the lower end of the shaft, seen at a right angle to Fig. 2.

Fig. 8 is a plan view of the under face of the bar on which the rabble blades are mounted.

Fig. 9 is a plan view of the under face of the shaft-supporting step.

Similar letters of reference indicate the same parts in all the figures.

A is a cylindrical tank which may be of cast iron, and B is a vertical shaft mounted axially therein, supported at the lower end on a step C and extending through a bearing A² in a bridge or frame A¹ mounted on the top of the tank. At the upper end of the shaft is a beveled gearwheel B² in mesh with a beveled pinion D¹ on a horizontal shaft D, mounted in bearings in the bridge A¹ and driven by a belt and pulleys, not shown, to rotate the shaft B in the direction indicated by the arrows in Fig. 3.

The tank has a removable plate or false bottom A³ and a removable lining A⁴ at the lower portion, designed to be replaced when worn by abrasion or corrosion.

At the extreme lower end of the shaft B is a socket B¹ adapted to inclose the step and hold the shaft centrally; the step comprises a stud C on a rectangular foot C¹ having holes C² in which are received corresponding pins or lugs on the bottom of the tank. The stud C is inclosed in a cylindrical bushing C³ held to the stud by a transverse pin c, and this fixed bushing is inclosed in a rotating bushing or lining ring B³ within the socket B¹ and held to the latter by a vertical pin b. The bushing and ring receive the wear of rotation and may be replaced when worn.

Above the socket B¹ is a rectangular transverse opening b¹ through the shaft B in which is received a bar E of rectangular section extending diametrically of the tank and held to the shaft by a locking-pin F extending axially upward from the stud C, projecting a short distance into the opening b¹ and engaged in a corresponding hole or recess e in the under face of the bar. The opening b¹ is of sufficient height to permit the bar to be introduced above the locking-pin F and then lowered into engagement with the latter when the hole e is in proper

relation thereto, and the locking is completed by the introduction of a close fitting filler J into the opening b¹ above the bar and serving to prevent an upward releasing 5 movement of the latter.

On each of the projecting ends of the bar E is mounted a series of rabble blades G forming the stirring arms. Each intermediate rabble blade comprises a head G¹ having a transverse opening g for the reception of the bar, and a forwardly projecting, downwardly inclined blade G terminating in a sharp beveled edge G², and reinforced by ribs G³ on the under face.

15 The blades G are the same for both series and they are slid successively upon the ends of the bar E by presenting such ends at the opening A⁵ provided in the side of the tank A as usual. Each arm of the bar is supplied 20 with its blades lying closely side by side; the series is then held in close contact and against the plane side faces of the shaft B by an outer blade H similar to but preferably wider than the intermediate blades 25 G, and having its head H¹ closed on the outer face, thus forming a closed pocket for the reception of the extreme end of the bar, to which it is held by a tapered pin h driven through the head and bar.

30 Thus built up the stirring arms are complete and perform the usual function of sweeping close to the surface of the false bottom A³, lifting and agitating the mass and effecting the intimate intermingling of 35 the ingredients necessary to insure the desired chemical combinations and changes.

It will be noted that the bar E is completely 40 inclosed and protected from both the corrosive and erosive action of the mass; therefore its renewal is infrequent and it may economically be of steel if preferred.

The rabble blades G lying closely adjacent the socket B¹ of the shaft B prevent any lateral movement of the filler J, thus insuring 45 against accidental displacement of the bar.

As the radius of travel and rate of speed is greater for the outer blades of the series than the inner, the latter wear more slowly 50 and may be retained when the outer blades require renewal, thus effecting a saving impossible with the usual arms in long single pieces; and as the castings forming the individual blades are comparatively small, 55 they may be of better and more refractory material than the usual single arms without great expense.

By supporting the shaft reliably on a step at the bottom of the tank, it is stiffly held 60 against gyratory movements; and therefore the edges of the blades may sweep the bottom A³ in exceedingly close proximity thereto while insured against scraping contact therewith.

65 By protecting the stud C of the step and

the interior of the socket B¹ with the bushing C³ and ring B³, the period of useful service of these important portions may be greatly prolonged; and by making the step removable it can be readily replaced when 70 necessary.

The locking pin F serves the double function of aiding to maintain the shaft B in axial alinement on the step and of affording a reliable holding means for the bar E 75 in conjunction with the filler J.

To remove the blades the shaft is turned to present one of the composite arms at the opening A⁵ of the tank; the tapered pin h is driven out, and the blades may then be 80 slid outwardly off the end of the bar and may be rearranged in replacing them or new blades substituted. In removing the bar E, both ends are stripped of blades; the filler J thus released is driven out, the bar lifted 85 clear of the locking-pin F, and by an endwise movement is withdrawn through the opening A⁵.

Although the invention is described as designed for service in anilin reducers, it 90 will be understood that it is applicable to other machines of like character to which it may be adapted.

Modifications may be made in the forms and proportions of the various portions, 95 and parts of the invention may be used without the whole.

I claim:—

1. In a machine of the character set forth, a tank, a vertical shaft therein, a bar mounted transversely in an opening in said shaft with its ends projecting oppositely, a series of rabble blades slidably mounted side by side on such ends and inclosing said bar, a locking-pin arranged axially of said shaft and engaged in said bar, and a filler in such opening holding said locking-pin and bar in engagement.

2. In a machine of the character set forth, a tank, a vertical shaft therein, a bar mounted transversely in an opening in said shaft, with its ends projecting in opposite directions, a locking-pin arranged axially of said shaft and engaged in said bar, a filler in said opening holding said locking-pin and bar in engagement, a series of rabble blades slidably mounted side by side on such ends and inclosing said bar, and means for securing the outermost blade of each series to said bar; and for holding said filler in such opening between adjacent innermost blades of the two series.

3. In a machine of the character set forth, a tank, a vertical shaft therein, a bar mounted transversely in said shaft with its ends projecting in opposite directions, a series of intermediate rabble blades slidably mounted side by side on such ends and inclosing said bar, and an outer rabble blade for each series, having a pocket receiving and covering 130

the outer extremity of such ends, and means for securing said outer rabble blades to said bar.

4. In a machine of the character set forth, 5 a tank, a vertical shaft therein having a socket at its lower end and a transverse opening above said socket, a bar extending through such opening and having a central recess in its lower face, a stud in said tank 10 received in said socket, a locking-pin vertically mounted in said stud and extending from said socket axially of said shaft to and partially across such opening, and adapted to engage such recess, a filler in 15 such opening on the upper face of said bar, and a series of rabble blades slidably mounted side by side on the projecting ends of said bar and inclosing the latter.

5. In a machine of the character set forth, 20 a tank, a vertical shaft therein having a socket at its lower end, a foot removably mounted on the bottom of said tank and having a vertical stud received in said socket and serving as a step for said shaft, and

stirrer arms extending radially from said 25 shaft.

6. In a machine of the character set forth, a tank, a vertical shaft therein having a socket at its lower end, a foot removably mounted on the bottom of said tank and 30 carrying a vertical stud, a bushing secured to said stud, a lining ring secured in said socket and adapted with the latter to inclose said stud and bushing, and stirrer arms extending radially from said shaft. 35

7. In a machine of the character set forth, a tank, a vertical shaft therein having a socket at its lower end, a foot mounted on the bottom of said tank and having a vertical stud received in said socket and serving as a step for said shaft, a bar mounted transversely in said shaft, a series of rabble blades slidably mounted on the ends of said bar and inclosing the latter and forming therewith oppositely extended stirrer arms. 40 45

In testimony that I claim the invention above set forth I affix my signature.

ALFRED H. STEVENS.
